UNITED STATES PATENT OFFICE.

CHARLES W. HERRIN, OF KANSAS CITY, MISSOURI, ASSIGNOR OF ONE-HALF TO
CLAYTON BELL, OF KANSAS CITY, MISSOURI.

PUMP.

Application filed December 18, 1925. Serial No. 76,249.

My invention relates to pumps and the present invention is an improvement over the pump disclosed by my copending United States application filed September 4, 1925, 5 Serial No. 54,475.

Objects of the present invention over the one disclosed by my above-mentioned application are to provide a pump of fewer parts which may be manufactured and assembled 10 at less cost, to provide a direct passage through the plunger rod to the pump barrel for the flow of oil instead of requiring the same to pursue a more tortuous path from the plunger rod into the plunger head and 15 thence into the pump barrel, and to dispense with the guide means 66 and 68 which direct the dogs 58 through the slots 56 for securing the plunger head to the plunger rod, as shown and described in said copending application.

In order that the invention may be fully understood, reference will now be had to the accompanying drawings, in which:

Fig. 1 shows a fragmentary vertical section of a well with the plunger head being slipped into position over the lower portion of the plunger rod preparatory to lowering the same into the pump barrel.

Fig. 2 shows the parts disclosed by Fig. 1, 30 with the plunger head occupying its normal position upon the lower section of the plunger rod which is lowered to working position in the pump barrel.

Fig. 3 is an enlarged detail vertical sectional view of the lower section of the plunger rod.

Fig. 4 is an enlarged detail vertical sectional view of the plunger head and associate parts.

Fig. 5 is an assembled view of the lower section of the plunger rod and the plunger head with associated parts, the plunger rod section being in elevation and the plunger head and associated parts in vertical section.

Fig. 6 is a cross section on line 6—6 of Fig. 5.

Fig. 7 is a view similar to Fig. 5, with the lower portion broken away and the tubular clamp lowered to hold the dogs firmly in engagement with the plunger rod.

Fig. 8 shows a fragmentary elevation of the tubular clamp with one of the slots therin for admission of one of the dogs.

Fig. 9 shows a fragmentary elevation of

the plunger head sleeve with one of the dogs 55 pivotally mounted therein.

Fig. 10 shows two detail perspective views of one of the dogs.

Referring now in detail to the different parts, A designates the usual well casing in 60 which the pump barrel 2 is arranged. The pump barrel 2 may be of any ordinary or preferred construction and is provided at its lower end with the customary foot valve 4, through which the oil is admitted to the interior of the pump barrel 2. The upper end of the pump barrel 2 is connected by a coupling 6 to tubing 8, which is supported at the upper end of the well in the usual manner.

10 designates the plunger rod which may be actuated from the top of the well in the usual manner, as by a pump jack not shown, and when in working position extends down into the lower portion of the pump barrel 2 75 as shown by Fig. 2. The lower section 12 of the plunger rod is of tubular form so that oil or other fluid may pass upwardly therethrough on each downward stroke of the plunger rod and discharge through ports 14 80 of a cage 16 detachably connecting the section 12 with the superimposed section of said plunger rod.

The cage 16 is equipped with a ball check valve 18, which opens on each downward stroke for the discharge of oil through the ports 14 and closes on each upward stroke of the plunger rod and thereby prevents the oil which has been discharged through the ports 14 from flowing backwardly 90 therethrough and into the section 12. The lower portion of the section 12 is equipped with leather or other suitable packing rings 20, which are held in position by the truncated conical seat 22 of a fitting 21 threaded upon 95 the lower end of said section 12. The fitting 21 has ports 24 and a solid bottom portion 26, which latter may, in the event that the foot valve 4 becomes loose, be employed as a hammer in forcing said foot valve firmly 100 down into the tapered lower end of the barrel 2 by moving the plunger rod up and down and permitting said bottom 26 to impinge against the upper end of said foot valve.

28 designates a plunger head sleeve 105 adapted to be slipped over the plunger rod and detachably connected thereto by one or more dogs 30, which are adapted to be forced

inwardly by the barrel 2 towards the tapered intermediate portion 34 of the section 12 and beneath a peripheral shoulder 36 at the upper end of said tapered portion 34, as shown by Fig. 5. The dogs 30 are mounted at their lower ends upon pivots 38 secured to the sleeve 28, and said dogs 30 are arranged in longitudinal slots 40 and 42 in the sleeve 28 and the lower portion of the tubular clamp 32, respectively, and thus prevent the latter from rotating in the former and carrying the slots 42 out of coincidence with the slots 40.

The dogs 30 have narrow body portions 44 adapted to move freely in the slots 40 and 42, and relatively broad heads 46 which are free to move only in the wide portions 48 of the slots 42. The heads 46 have inclined lower portions 50 against which the beveled shoulders 52 at the lower edges of the wide portions of the slots 42 contact when the clamp 32 is raised to the position disclosed by Fig. 4, and thus throw the dogs 30 out of engagement with the section 12, so that the plunger head, hereinafter more fully described, may be removed from the well without removing the plunger rod, as is the usual custom.

The sleeve 28 has threaded in its upper end a tubular extension 54 having a beveled upper margin 56 for disengaging elevator dogs 150 from a peripheral collar 58 at the upper portion of the clamp 32, which is provided at its extreme upper end with a second peripheral collar 60 for engagement by the elevator dogs 150, as will hereinafter appear. For convenience in assembling the sleeve 28 and the tubular clamp 32, said sleeve 28 is detachable from the extension 54 and said clamp 32 is made in detachable upper and lower sections 62 and 64, respectively, threaded together as indicated at 66.

The elevator mechanism embodying the dogs 150 is preferably of the type disclosed in my copending application filed July 6, 1925, Serial No. 41,660.

The tubular clamp 32 is slidably mounted in the sleeve 28 and the extension 54, in order that it may be lowered to lock the dogs 30 in the active position disclosed by Fig. 7, or raised to free the dogs as shown in Fig. 4. The upward movement of the clamp 32 in the sleeve 28 and the extension 54, is checked by the enlarged upper end of its lower section 64 contacting the lower end of said extension 54, while the downward movement of said clamp 32 is checked by the upper ends 65 of the slots 42 contacting the upper ends of the dog bodies 44.

The lower reduced end of the sleeve 28 is threaded into the upper end of a tubular fitting 70 carrying a plurality of leather or other suitable packing cups 72 held apart by spacing elements 74, all of which are held in place by a nut 76 threaded upon the lower end of said tubular member 70. The nut 76

has a tapered bore 78 adapted to fit snugly upon the seat 22 and coat with the packing rings 20 in preventing oil from entering the annular joint between the lower section 12 of the plunger rod and the tubular fitting 70 of the plunger head, which latter consists of the sleeve 28, the packing cups 72, the spacing elements 74, and said nut 76.

Springs 80 secured at their lower ends to the sleeve 28 and fitting within longitudinal grooves 82 at the inner sides of the dogs 30 serve to hold the latter outwardly in the position disclosed by Fig. 4, while the plunger head is being lowered over the plunger rod and through the tubing 8.

The operation briefly stated, is as follows: Assuming that the packing cups 72 have become worn and no longer operate efficiently in sucking oil into the barrel 2 through the foot valve 4, the plunger rod 10 is lifted with the plunger head into the tubing 8 by the usual plunger rod hoisting mechanism located at the top of the well. After the lower end of the plunger rod with the fitting 21 has been raised clear of the top of the barrel 2 as shown by Fig. 1, the plunger rod hoisting mechanism is stopped so that the plunger rod will remain stationary. The elevator mechanism is then lowered to engage the dogs 150 with the underside of the collar 60, and then hoisted to the surface with the plunger head. As the elevator mechanism starts upwardly it first raises the tubular clamp 32, causing the upper end of the lower section 64 to contact the lower end of the sleeve extension 54, whereupon the entire plunger head is hoisted. As the tubular clamp 32 initially moves upwardly independently of the sleeve 28, the wide portions of the slots 48 are carried into position to free the upper ends of the dogs 30, so that they may be forced outwardly by the springs 80 from beneath the shoulder 36 of the plunger rod section 12. In the event, however, that the springs 80 should fail to force the dogs 30 outwardly as stated, said dogs are positively forced outwardly by the beveled shoulders 52, which contact the beveled portions 50 of the dogs and force the latter outwardly before the upper end of the section 64 contacts the lower end of the extension 54. When the dogs 30 are freed from the plunger rod section 12 as stated, the plunger head is free to be lifted to the surface independently of the plunger rod.

After the worn packing cups 72 have been replaced by others, the plunger head is lowered over the plunger rod by the elevator mechanism, the dogs 150 of which engage the underside of the collar 58. As the plunger head moves downwardly the heads 46 of the dogs 30 are held outwardly beneath the upper ends of the wide portions 48 of the slots 42 by the springs 80, so that there will be no danger of the plunger head falling

due to the clamp 32 moving down into the sleeve 28 far enough to allow the dogs 150 to be prematurely released from the plunger head by the beveled upper end 56 of the extension 54.

After the plunger head reaches the conical seat 22 on the plunger rod 10, the same is lowered with the plunger head into working position in the pump barrel 2. As the plunger head enters the barrel 2, the friction of the cups 72 against the inner surface of said barrel will retard the downward movement of the plunger head sufficiently to permit the clamp 32 to move down somewhat faster than said plunger head until checked by shoulders 67 contacting the upper ends of the dogs 30. The wide portions 48 of the slots 42 are now presented to the heads 46 of the dogs 30, so that the same may be forced inwardly by the barrel 2 beneath the shoulder 36 of the plunger rod section 12. As the dogs 30 are forced inwardly by the barrel 2, the clamp 32 moves downwardly until checked by the ends 65 of the slots 42 contacting the upper ends of the bodies 44 of the dogs 30, the heads 46 of which are firmly forced by the shoulders 67 into engagement with the tapered portion 34 of the section 12, so that the plunger head will be firmly secured to said section 12 and move up and down therewith when the pump is in operation. Downward movement of the clamp 32, as stated, also permits the elevator dogs 150 to contact the beveled end 56 of the extension 54, which releases said dogs 150 from the collar 58, so that the elevator mechanism can be lifted to the surface.

From the foregoing description, it is apparent that I have provided mechanism whereby the plunger head may be removed from the well independently of the plunger rod, thereby saving the time and expense of pulling said plunger rod from the well, the expense of which increases with the depth of the well.

While I have shown and described the preferred form of the invention, I reserve all rights to such changes and modifications thereof as properly fall within the spirit and scope of the invention as claimed.

Having thus described my invention, what I claim and desire to secure by Letters Patent, is:

1. In an apparatus of the character described, a plunger rod having a tubular section with a lower truncated conical portion, a plunger head arranged to be slipped over said section and having an internal tapered portion to snugly fit around said truncated conical portion, and pivotal means for detachably securing said plunger head in position upon said plunger rod section so that the plunger head may be raised to the surface of a well independently of the plunger rod.

2. In an apparatus of the character described, a plunger rod section having a passageway extending longitudinally therethrough, a check valve at the upper end of said passageway, a plunger head mounted upon said section and terminating at a point below said valve, a pump barrel in which said plunger head is reciprocably mounted, a foot valve mounted in the lower portion of said barrel, dogs mounted on the plunger head and arranged to be forced by the pump barrel into engagement with the plunger rod section, and annular clamp means connected to the plunger head and adapted to engage over said dogs and secure the latter in engagement with the plunger rod section.

3. In an apparatus of the character described, a plunger rod, a tubular plunger head arranged to be slipped over said plunger rod, a dog associated with said plunger head and adapted to detachably secure the same to the plunger rod, and clamp means adapted to be slipped downwardly over said dog for securing the latter in active position.

4. In an apparatus of the character described, a plunger rod, a plunger head adapted to be slipped over said plunger rod, a dog mounted on said plunger head and adapted to engage the plunger rod, and annular clamp means slidably associated with said plunger head and adapted when slid in one direction to clamp said dog in engagement with the plunger rod when slid in a reverse direction to disengage the dog from the plunger head.

5. In an apparatus of the character described, a plunger rod, a plunger head adapted to be slipped over said plunger rod, a dog mounted on said plunger head and adapted to engage the plunger rod, and clamp means slidably mounted within said plunger head and having a slotted portion which clamps the dog in engagement with the plunger rod when said clamp means is slid in one direction and releases the dog from the plunger rod when said clamp means is slid in a reverse direction.

6. In an apparatus of the character described, a plunger rod, a plunger head adapted to be slipped over said plunger rod, a dog mounted within said plunger head and having a narrow body portion and a relatively wide head, and clamp means for detachably clamping said dog against the plunger rod and slidably mounted within the plunger head, said clamp means having a slot with a wide portion to permit the head of the dog to engage or disengage the plunger rod, a narrow portion into which the body of the dog projects, and shoulders at the juncture of the wide and narrow portions of said slot for disengaging the dog from the plunger rod when the clamp means is slid in a reverse direction to that in which

it is slid to carry the wide portion of the slot into coincidence with the head of the dog.

7. In an apparatus of the character described, a plunger rod, a plunger head adapted to be slipped over said plunger rod, a dog mounted within said plunger head, spring means for holding said dog outwardly so that it will be forced inwardly by the pump barrel when lowered into the same, and clamp means for clamping said dog against the plunger rod after said dog has been forced inwardly by the pump barrel.

8. In an apparatus of the character de-

scribed, a plunger rod having a tapered portion surmounted by an annular shoulder, a plunger head adapted to be slipped over said rod, dogs mounted within said plunger head and adapted to engage the tapered portion of the plunger rod, and clamp means slidably associated with said plunger head and adapted when slid in one direction to clamp said dogs against the plunger rod and when slid in a reverse direction to release said dogs.

In testimony whereof I affix my signature.

CHARLES W. HERRIN.
